UNITED STATES PATENT OFFICE.

SEID G. BACK AND BERT L. DOLLOFF, OF PORTLAND, OREGON.

FRAUD-PREVENTING DEVICE FOR COIN-CONTROLLED APPARATUS.

1,276,001.

Specification of Letters Patent. Patented Aug. 20, 1918.

Application filed September 22, 1917. Serial No. 192,764.

To all whom it may concern:

Be it known that we, SEID G. BACK and BERT L. DOLLOFF, citizens of the United States, residing at Portland, in the county 5 of Multnomah and State of Oregon, have invented new and useful Improvements in Fraud-Preventing Devices for Coin-Controlled Apparatus, of which the following is a specification.

10 This invention relates to a fraud preventing device for coin controlled apparatus, and one of the objects is to provide a device which may be connected with the coin receptacle of a telephone, or may be connected 15 with a vending machine for the purpose of detecting blanks or slugs which may be inserted, and which will also serve to detect light weight coins.

Another object is to provide a construction 20 suitable for use in connection with any coin operated mechanism, and which may be incorporated in the machine proper at the time of the manufacture thereof.

A further object is to provide a construction 25 which shall be electrically controlled under certain conditions, and which shall be under electro-magnetic control in the event that slugs of iron or the like are employed.

30 With the foregoing and other objects in view, the invention consists in the novel construction hereinafter described, and including a pivoted weighing chute in which a coin or slug is discharged from the receiving device, this chute being so mounted and so controlled that the slug or light weight coin will be discharged from one end thereof without operating the weighing chute, and will be returned to the individual depositing 35 the article, whereas a genuine coin of proper weight will operate the weighing chute and cause the discharge of the coin into the receptacle provided for that purpose.

In the drawings:

45 Figure 1 is a top plan view of the apparatus mounted on a suitable base.

Fig. 2 is a vertical section through the casing showing the apparatus in side elevation.

50 Fig. 3 is a vertical transverse section on the line 3—3 of Fig. 2.

Figs. 4, 5 and 6 are views in elevation showing different positions of the chutes.

55 Fig. 7 is a diagrammatic view of the circuits.

A balanced weighing chute is designated 10 and is mounted in a fixed position in yoke 12, the latter being pivotally mounted at 14 in a U-shaped frame 15.

Secured to the under side of chute 10 is a 60 cross arm 16 carrying thereon threaded pins 17 and 18 which serve to mount weights 19 and 20 arranged for adjustment by reason of the threaded connection, and secured in position when adjusted by means of set 65 screws 21 and 22. This adjustment makes it possible to set the apparatus for operation by means of coins of different sizes or denominations.

The opposite end of the weighing chute 70 10 carries a laterally extending device 24 in which is mounted an adjusting screw 25 carrying a contact member 26. A mercury cup 27 is mounted on the base 28 and a second contact member 30 extends into this cup 75 and is mounted on the arm 31 pivoted at 32 in a bracket 33 insulated from the base, the opposite end of the pivoted member serving to carry a discharge chute 35 which is downwardly inclined as shown and is positioned below the discharge end of weighing chute 10. The discharge chute is insulated from pivoted member 31.

A coin receiving chute is designated 40 and is mounted in a fixed position in a yoke 85 41 which latter is pivotally mounted at 42 in frame 15. One end of this chute carries a weight 44 serving to normally retain the corresponding end of the chute in a lower position, and the same end of the chute carries a laterally extending lug 46 through which passes a screw 47 contacting with the frame 15 and designed to limit the extent of movement of chute 40. A screw 48 passes through the lower member 16 and contacts with frame 15 for the purpose of limiting the movement of chute 10.

100 Chute 40 carries a laterally extending arm or bracket shown at 49 in which is mounted at the outer end a threaded member 50 carrying a contact member 51 extending into mercury cup 52. A lower terminal for cup 52 is shown at 53 and is in electric connection with a bracket 54 mounted on an insulating block 55 carried upon the frame 15.

The casing 60 serves to house the apparatus and is provided with a slot 61 through which the coin is deposited, the coin passing thence to chute 40. The casing 60 is also provided with a slot 62 opposite one end of 110

chute 10 through which blanks, slugs or light weight coins are discharged for return to the individual depositing the latter. Genuine coins are discharged through the slot 58 in the base and thence pass through slot 59 of the casing into the coin receptacle of the telephone or vending machine as the case may be.

If a blank or slug is deposited and is received within the chute 40 at the end 40' thereof it will cause said chute to move downwardly at that end and will complete a circuit through magnet 65 by reason of the contact through member 51, and if the slug or blank be of iron or the like, it will fall nearer to the center of the chute end than if of non-magnetic material, being deflected by the magnetized arm 74' on one of the poles and falling nearer to the center as indicated it will fail to operate chute 10, that is it will fail to depress the end 10' thereof, and the chute being downwardly inclined toward the opposite end, the blank or slug will be discharged through the slot 62 of the casing and will be returned to the individual depositing the article. During the discharge of the coin from chute 40 contact was broken through member 51 by reason of the downward movement of the opposite end of chute 40 under the influence of the weight 44 and the circuit through magnet 65 was therefore broken and the blank or slug was no longer acted upon magnetically.

A genuine coin of proper weight if dropped into chute 40 will cause the latter to tilt downwardly at the end 40' thereof, the coin falling into chute 10 in a position nearer to the end 10' than that above indicated in connection with the movement of a blank of iron or the like. The coin passing from chute 40 will cause contact through member 51 to be broken owing to the movement of the chute downwardly and rearwardly under the influence of the weight 44, this circuit having been completed when the coin was first dropped in chute 40.

The shock incident to the falling of the coin from chute 40 into chute 10 will force downwardly the end 10' of said chute and will complete a circuit through contact 26 and through contact 30 within the mercury cup 27, serving to energize magnet 65 and its pole extension 65' and therefore will cause said chute 10 to move slightly farther and to be held in a lower position long enough to permit the coin to pass out of the end 10' and into the discharge chute 35 previously mentioned, passing thence through the slot 58 into the coin receptacle. The position of the coin at the end of chute 10, as it is about to be discharged is illustrated in Fig. 6.

If a genuine coin deposited as above indicated is not of sufficient weight to operate the device when properly adjusted, and it

is not desired that the coin shall pass into the coin receptacle, this coin will pass from the end of chute 10 adjacent to the slot provided for the discharge and return of slugs and blanks, the weights 19, 20 serving to return that end of the chute to its lower position after the first shock due to the falling of the coin into the chute, the force exerted by the coin in falling having been insufficient to depress the end 10' of the chute to such an extent as to make electric contact through member 26.

It will therefore be apparent that the weighing chute 10 is operative for discharging coins into the coin receptacle only when the latter are of the proper weight, and that it cannot be operated by a blank or slug even if of proper weight, in the event that the article is of iron or the like and therefore subject to magnetic influence.

The magnet is only momentarily energized when the circuit is completed through the upper contact 51 and cup 52, and the coin immediately falls from chute 40, and the period during which the magnet is energized is so short that the weighing chute will not have time to respond in the manner specified upon the completion of the circuit through mercury cup 27.

The circuit is finally broken through the upward movement of contact 30 when the coin forces the pivoted discharge chute 35 downwardly.

When the circuit is closed by making contact through member 51 and the mercury cup 52 current flows from terminal 75 of the battery through wire 76, wire 77, lower contact 33 of the cup thence to the contact 51 through the chute 40, the frame 15, wire 78 to the magnet 65, wire 79 to terminal 80 of the battery.

The circuit through the mercury cup 27 is as follows:

From terminal 75 of the battery through wire 76, bracket 33, arm 31, contact 30, contact 26, chute 10, frame 15, wire 78, magnet 65, wire 79 to the battery terminal 80.

What is claimed is:

1. In a device of the class described, a pivoted weighing chute normally inclined and discharging coins from the end normally elevated and discharging rejected objects from the opposite end, a pivoted receiving device, a magnet, and means for energizing the magnet by the movement of the pivoted receiving device for deflecting a check capable of being magnetized and causing it to drop into the inclined weighing chute at a predetermined point with reference to its pivotal mounting and without operating said weighing chute, the check being discharged from the chute by gravity.

2. In a device of the class described, a pivotally mounted and weighted receiving device, a magnet and means for completing

a circuit therefor upon the pivotal movement of the receiving device, a pivotally mounted weighing chute operated by an object of a given weight not responsive to the 5 action of a magnet, means for energizing the magnet when the weighing chute is operated, a frame in which said chutes are mounted, said frame forming a part of the electrical connection between the chutes and the magnet, 10 a pivoted discharge chute, and mounting means therefor, said discharge chute being positioned to partly support the object received from the weighing chute, the weighing chute moving under impact of the object and completing a circuit through the 15 mounting means of the discharge chute and through the magnet, for effecting discharge from the weighing chute, the operation of the discharge chute by the object breaking the circuit.

3. In a device of the class described, a pivotally mounted and weighted receiving device, a magnet and means for completing

a circuit therefor upon the pivotal movement of the receiving device, the magnet 25 being positioned for influencing the path of movement of a check of iron or the like, a pivotally mounted weighing chute normally inclined and operated by an object of a given weight not responsive to the 30 action of a magnet, a pivotally mounted discharge chute positioned to partly support the object when ready for discharge from the weighing chute, means for energizing the magnet when the weighing chute is operated, 35 said magnet causing the further operation of the weighing chute for delivering the coin to the discharge chute, and means for breaking the circuit of the magnet upon the pivotal movement of the discharge chute under impact of the coin delivered thereto.

In testimony whereof we affix our signatures.

SEID G. BACK.
BERT L. DOLLOFF.
